F. F. WULKOP

GOLF TEE

Filed April 2, 1925

FIG. 1.

FIG. 3.

FIG. 2.

Inventor.

F. F. Wulkop

By

J. K. Bryant
Attorney

UNITED STATES PATENT OFFICE.

FREDERICK F. WULKOP, OF GENEVA, NEW YORK.

GOLF TEE.

Application filed April 2, 1925. Serial No. 20,129.

To all whom it may concern:

Be it known that I, FREDERICK F. WULKOP, a citizen of the United States of America, residing at Geneva, in the county 5 of Ontario and State of New York, have invented certain new and useful Improvements in Golf Tees, of which the following is a specification.

This invention relates to new and useful 10 improvements in supports, and it pertains particularly to a support known as a golf tee, and especially designed for supporting a golf ball in a driving position.

The primary object of this invention is 15 to provide a new and useful golf tee, which will support a golf ball in such a manner, as to permit of the golf ball being driven therefrom with a club without injury to the tee, thereby affording a golf tee which may 20 be reused over and over.

Another object of this invention is to provide a device of the above mentioned character, adapted to be adjusted to meet the requirements of different sized players, and 25 can also be used for teeing off of an uneven surface.

A still further object of this invention is 30 to provide a golf tee, which is portable, unbreakable, compact and easily carried in one of the pockets of the player.

Other objects and advantages of the invention will be apparent during the course 35 of the following description.

In the accompanying drawing forming a 40 part of this specification and in which like numerals are employed to designate like parts throughout the same,

Figure 1 is a vertical sectional view of the 45 preferred embodiment of my invention, showing the device inserted in the earth and supporting a golf ball.

Figure 2 is a top plan view of the same,

Figure 3 is a vertical side elevational view 50 of a modification embodying my invention showing the shank and adjustable cup-shaped receptacle partly in section,

Figure 4 is a top plan view of Fig. 3, showing the adjustable, cup-shaped receptacle detached from the shank.

In the drawing, wherein for the purpose 55 of illustration is shown a preferred embodiment of my invention, attention first being called to Fig. 1 wherein the numeral 5 designates a peg, conical in shape and preferably of a rigid material such as hard rubber, bakelite, wood or the like, an annular

flange 6 being formed integral with the conical-shaped peg near the top thereof adapted to limit the downward movement of the device when inserted in the earth. 60

A shank 7, is formed at the uppermost portion of the peg 5. Mounted upon this shank is a cup-shaped receptacle 8, preferably formed of a flexible material such as soft rubber, so that it will not break off of 65 the shank 7, should the player by chance miss his aim and hit the cup-shaped receptacle 8. The cup-shaped receptacle 8, is attached to the shank by any suitable adhesive, such as shellac, glue, or vulcanizing 70 designated by the numeral 9. The cup-shaped receptacle 8, is recessed at 10, to form a pocket or seat for the golf ball 11.

In Fig. 3, is shown a modification of my invention wherein the numeral 12 designates 75 a conical-shaped peg similar to that shown and described in Fig. 1 and also of a rigid material, a flange 13 being formed integral on the uppermost portion thereof to limit the downward movement of the device when 80 inserted in the earth. A shank 14 is formed near the top of the peg 12.

A cup-shaped receptacle 15, is provided 85 with a recess 16, adapted to receive the shank 14, for allowing the said receptacle 15 to be adjusted thereon by sliding the cup-shaped receptacle 15, up or down on the shank 14, as the player may desire. Wire eyelets 17 and 18 are embedded in the shank 14 and cup-shaped receptacle 15 respectively 90 for connecting the cup-shaped receptacle 15 to the shank 14 by means of a cord 19.

For a consideration of the operation of the device, attention is first called to Fig. 1. This device may be taken between the 95 two fore fingers of the player, and inserted or wedged into the earth by asserting a downward pressure on the annular flange 6, until the annular flange 6 is flush with the surface of the earth, the golf ball is then 100 seated in the recess 10 of the cup-shaped receptacle 8, and the ball is ready to be teed off.

In Fig. 3 the device may be adjusted to suit the height of the player by moving the 105 cup-shaped receptacle 15, up or down on the shank 14. Should the player by chance, strike the cup-shaped receptacle 15, with his club, while teeing off the receptacle will not be carried away from the player, and 110 lost. This novel feature is accomplished by anchoring the cup-shaped receptacle 15 to

the shank 14 of the peg 12 by means of a cord 19.

It is to be understood that the form of my invention herewith shown and described, 5 is to be taken as a preferred example of the same, and that various changes in the shape, size, and arrangement of parts may be resorted to without departing from the spirit of the invention or the scope of the sub-10 joined claims.

Having thus described my invention, I claim:—

1. In a golf tee, a conical-shaped peg formed of hard rubber, an annular flange 15 formed with and of the same material as the peg, to limit the downward movement of the peg when inserted in the earth, a shank formed on the uppermost portion of the peg and of the same material as the

latter, and a cup-shaped receptacle formed 20 of soft rubber carried by the shank.

2. In a golf tee, a conical shaped peg, an annular flange formed integral with the peg, to limit the downward movement of the latter when inserted in the earth, a 25 shank formed on the uppermost portion of the peg, a cup-shaped receptacle having a recess, adapted to receive the shank, for permitting adjustment of the cup-shaped receptacle to different heights from the 30 ground, eyelets mounted in the shank and cup-shaped receptacle respectively and a tying element for connecting the eyelets to keep the cup-shaped receptacle from being distantly removed from the shank. 35

In testimony whereof I affix my signature.

FREDERICK F. WULKOP.
